UNITED STATES PATENT OFFICE.

CHARLES M. ALLEN, OF BASIN, MONTANA.

CALCINING-FURNACE.

SPECIFICATION forming part of Letters Patent No. 633,777, dated September 26, 1899.

Application filed July 27, 1898. Serial No. 686,977. (No model.)

To all whom it may concern:

Be it known that I, CHARLES MAURICE ALLEN, of Basin, in the county of Jefferson and State of Montana, have invented a new and Improved Calcining-Furnace, of which the following is a full, clear, and exact description.

The object of the invention is to provide certain new and useful improvements in calcining-furnaces whereby the material under treatment is thoroughly calcined in a comparatively short time and very economically as to the use of fuel and whereby the material is relieved of its moisture previous to its entrance into the hearth to prevent the formation of sulfuric acid, so destructive to the hearth and the traveling and stirring devices as experienced in furnaces heretofore constructed.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a sectional elevation of the improved furnace. Fig. 2 is an enlarged longitudinal elevation of the rear end of the same. Fig. 3 is a sectional plan view of the same. Fig. 4 is an enlarged sectional elevation of the forward end of the lower hearth. Fig. 5 is an enlarged transverse section of the improvement on the line 5 5 in Fig. 1. Fig. 6 is an enlarged plan view of the stirring devices. Fig. 7 is a transverse section of the extension for the lower hearth with the receiving-floor for the material, the section being through one of the supporting-arches on the line 7 7 in Figs. 1 and 9. Fig. 8 is a similar view of the extension for the lower hearth, the section being on the line 8 8 in Fig. 1.

Fig. 9 is a sectional side elevation of the receiving or drying floor on the lower hearth extension, the section being on the line 9 9 in Fig. 7. Fig. 10 is an enlarged transverse section of the improvement, on the line 10 10 in Fig. 1, and showing the fire-box for the lower hearth. Fig. 11 is a similar view of the same on the line 11 11 in Fig. 1 and showing

the fire-box for the upper hearth. Fig. 12 is an enlarged sectional side elevation of the shoe carried by the stirring device for opening the hearth-doors. Fig. 13 is an edge view of the same. Fig. 14 is an enlarged plan view of the rail. Fig. 15 is a side elevation of the same. Fig. 16 is a plan view of one of the rail-chairs. Fig. 17 is a side elevation of the same, and Fig. 18 is a cross-section of the rail and chair.

The calcining-furnace is built of the usual masonry and with an upper or entrance hearth A and a lower or discharge hearth B, both connected with each other at their rear ends by a drop-opening C, which allows the material under treatment and moved rearward in the hearth A in the direction of the arrow a' to finally drop through said opening 70 into the lower hearth B to be moved forward therein in the inverse direction of the arrow a'. The material in the hearths A and B is agitated and moved therein in the direction described by suitable continuous-stirring devices D, passing through both hearths in the direction of the arrows, each stirring device being provided with angular plows D', (see Fig. 6,) mounted on a suitable carriage D², adapted to travel on rails E, held in the bottoms of the hearths, as hereinafter more fully described, said carriages being attached to an endless chain D³, passing over wheels D⁵ and D⁶, located at the rear and front ends of the lower hearth B, as is plainly illustrated 85 in Figs. 1, 2, 3, and 4, said wheels being secured on shafts D⁷, journaled in suitable bearings and connected at their outer ends by a pulley D⁸ and a belt to other machinery for imparting a rotary motion to the shafts to 90 cause the wheels D⁵ D⁶ to impart a traveling motion to the chain D³, and thereby move the stirring devices through the hearths. The plows D' of successive stirring devices are preferably arranged in opposite directions 95 relatively to each other, as will be readily understood by reference to Fig. 6.

The forward end of the lower hearth B is formed with an extension B', extending beyond the front end of the upper hearth A, 100 (see Fig. 1,) and part of the top of this extension forms a receiving and drying floor B² for the material under treatment, said material being discharged upon the forward end

of the floor by a traveling belt F, receiving the material from a mechanical feeder F' of any approved construction.

The floor B² is preferably formed of cast-
5 iron plates B³, having side flanges B⁴ (see
Figs. 7 and 9) to prevent the material from
falling over the sides of the floor when moved
forward by the action of the stirring devices.
The floor B² is on a level and in alinement
10 with the bottom of the hearth A, and the stir-
ring devices in passing over said floor move
the material rearward and into the upper
hearth A. Said stirring devices being exposed
15 to the open air are thus cooled while passing
over said floor and over the outer portion of
the roof of the extension B', and which outer
portion is not used as a drying-floor for the
ore. The extreme outer portion of the top
20 of the extension B' is simply provided with
supports for the rails E, but not with a floor.
(See Fig. 8.)

Part of the top of the extension-hearth B'
(see Figs. 7 and 9) and the plates B³ are di-
rectly and highly heated by the heat of the
25 extension-hearth, and said plates are capable
of imparting this heat to the ore on the floor,
and consequently the ore moved over the
floor B² by the stirring devices is almost com-
pletely relieved of its moisture before the ore
30 enters the upper hearth and before said mois-
ture can combine with the sulfur fumes pro-
duced in the hearth to form sulfuric acid,
the corrosive action of which is so detri-
mental to the life of the furnace.

35 The floor B² is of considerable length, and
in practice it requires several hours for the
ore to travel from the outer end of the floor
B² to the entrance of the upper hearth A, and
hence the heat from the floor B² has sufficient
40 time to expel the moisture in the ore.

The plates B³ forming the floor B² are riv-
eted or otherwise fastened to transverse an-
gle-irons B⁵, set in chairs B⁶, supported on
transverse arches, spaced apart, as indicated
45 in Fig. 9, the outer ends of the angle-irons
being secured to the binding-rods for the
masonry of the furnace. Thus by the ar-
rangement described the floor-plates B³ are
directly subjected to the heat emanating
50 from the burning material passing through
the lower hearth B in the inverse direction
of the arrow a'.

The forward end of the upper hearth A is
provided with a suitable fire-box G, (see Figs.
55 1 and 11,) and a similar fire-box G', (see Figs.
1 and 10,) leads to the lower hearth B, some-
what in front of the drop-opening C; but
other additional fire-boxes may be located in
60 the masonry at intervals throughout the
length of the hearths A and B, and the latter
may also be provided at intervals with suit-
able doors G², as indicated in Figs. 2, 3, 4,
and 5.

In order to make the hearths A and B
65 practically continuous, to avoid loss of heat,
and to prevent air from entering at the rear
ends of the hearths A and B, I provide a cas-

ing or hood H, secured to the ends of the
hearts and inclosing the wheel D⁵ and the
stirring devices passing over the same in their 70
passage from the upper hearth A to the lower
hearth B. (See Figs. 1 and 2.) The rear
ends of the hearths A and B are in addition
normally closed by self-closing doors I I', and
similar doors I² I³ normally close the front 75
ends of the hearths A B, respectively, and all
of said doors are automatically opened in ad-
vance of an approaching stirring device by
shoes I⁴, carried on the carriage of said de-
vice, as is plainly shown in Figs. 6, 12, and 13. 80

The forward end of the lower hearth B is
provided at its bottom with an outlet B³, lead-
ing to the throat J' of a large storage-hopper
J, connected by a hot-air flue with the main
85 stack to permit escape of the gases passing
with the material from the lower hearth B
into said hopper. The latter is built directly
over a reverberatory smelting-furnace, of any
approved construction but not shown, so that
the calcined material accumulating in the 90
storage-hopper from the calcining-furnace
may be directly discharged into the smelting-
furnace, according to the requirements of the
latter.

From the foregoing it is evident that as the 95
two hearths A and B are practically continu-
ous the fire travels through the material in
the direction indicated by the arrows in Fig.
1 from the upper hearth to the lower hearth
without loss of heat to insure a proper calcina-
tion of the material without a great expendi-
ture of fuel in the fire-boxes. It will further
be seen that by the arrangement described
the air that enters the front end of the upper
hearth A by way of its fire-box G travels to 100
the back of the hearth and then through the
opening C, then descends into the lower
hearth and travels forward therein to finally
reach the stack connection by way of the
hopper, as previously explained, and by this 105
arrangement the heat travels through the ore
and is introduced at the point where the ore
is comparatively cold, and the heat is carried
through the ore during the entire operation
of calcining. As no outer cold air passes into 110
the lower hearth and its extension B', it is
evident that the said extension and the dry-
ing-floor B², forming part of the roof for the
extension, do not become cooled, and conse-
quently a proper drying of the ore takes place 115
on said floor, and a final proper calcining of
the ore is carried on in the extension previ-
ous to the discharge of the ore into the throat
J' of the hopper J.

The heat from the burning material trav-
eling in the extension B' of the lower hearth
heats the floor B² sufficiently to properly dry
the material coming from the mechanical
feeder F', so that very little, if any, sulfuric
acid (H₂SO₄) is produced in the hearth A, as 120
is so frequently the case in calcining-furnaces,
as heretofore constructed.

It is well known that sulfuric acid is very
destructive to the material of which the hearth

is built, and consequently, as very little, if any, sulfuric acid is generated in the hearth, the life of the hearth is greatly lengthened. The extension B' of the lower hearth gives 5 considerable length for the material to travel in and on its top it heats and dries the fresh ore and allows the stirring devices to cool after leaving the forward end of the lower hearth B and before reentering the upper 10 hearth A. Should any outside air pass into the forward end of the upper hearth A, it passes through the fire emanating from the fire-box G, and thus becomes heated and useful in the furnace, and any air passing into 15 the forward end of the lower hearth goes directly into the throat J' of the hopper J and to the stack, so that said outer air is prevented from lowering the temperature of the lower hearth, and hence more effective calcining takes place in a comparatively short 20 time and with the least amount of fuel.

In furnaces as heretofore constructed the rails for the carriage of the stirring devices usually buckle and warp from the intense 25 heat within the hearth, and in order to prevent this I provide the following construction: The rails E are bolted to vertically-disposed lugs E² on the chairs E', made in the form of flat plates, bolted to or set on the bottom 30 plates, carrying the brick bottom for the hearth, and the brick bottom covers the chair, as is plainly shown in Figs. 7 and 8. The bolt-holes E³ in the rails E (see Fig. 15) are slotted longitudinally to allow expansion and 35 contraction of the rails exposed to the heat in the hearth without straining the chairs. The ends E⁴ of the rails E are beveled in opposite directions, as is plainly shown in Figs. 14 and 15, to form cutting edges, so that when 40 the rails expand by the heat they can readily cut their way through the brick floor and the ore on the floor. The upper portions of the ends E⁴ are formed with beveled projections E⁵, so that adjacent rails overlap by their projections E⁵ to render the track continuous, it 45 being understood that the ends E⁴ of adjacent rails are set about an inch apart when laying the track to make provision for expansion when the furnace is heated up. The ends E⁶ 50 of the chair-plates and the ends E⁷ of the lugs E² are also beveled to form cutting edges, so that when the chairs expand the edges readily cut their way in the brick bottom without bulging the plates or displacing the brick. 55 From the foregoing it will be seen that the rails can expand and contract without danger of bulging and without affecting thereby the chairs, and the latter expand and contract irrespective of the rails and without danger 60 of warping and heaving the brick bottom of the hearth.

Having thus fully described my invention, I claim as new and desire to secure by Letters Patent—

65 1. A calcining-furnace provided with a plurality of hearths located one above the other, the uppermost hearth being shorter than the

hearth beneath it, leaving one end of the roof of the lower hearth exposed to form a drying-floor leading to the entrance of the upper 70 hearth, said drying-floor being capable of freely taking up the high heat emanating from the burning material traveling through the lower hearth, and the said floor being also capable of imparting such heat to the material 75 discharged upon the drying-floor, to expel the moisture from said material during its travel over said floor and previous to its entrance into the upper hearth at or near the entrance ends thereof, inlets for the products of combustion to the said hearths at or near the entrance ends thereof and an outlet for the products of combustion at the discharge end of the lower hearth.

2. A calcining-furnace provided with a plurality of hearths located one above the other, the uppermost hearth being shorter than the hearth beneath it, leaving one end of the roof of the lower hearth exposed to form a drying-floor leading to the entrance end of 90 the upper hearth, the other end of the upper hearth being connected with the unexposed end of the lower hearth which is provided with a discharge at or near the end of its exposed portion, the material to be treated traveling over said drying-floor and through the upper hearth in one direction, to then travel in the reverse direction in the lower hearth, said floor being capable of freely taking up the high heat emanating from the outwardly-moving material in the exposed portion of the lower hearth, said floor being also capable of imparting such heat to the material traveling over it, to expel the moisture previous to the material passing into the upper 95 hearth at or near the entrance ends thereof, means for traversing the material over the said drying-floor, inlets for the products of combustion to the said hearths at or near the entrance ends thereof and an outlet for the products of combustion at the discharge end of the lower hearth.

3. A calcining-furnace provided with a plurality of hearths located one above the other, the uppermost hearth being shorter than the 115 hearth beneath it, leaving one end of the roof of the lower hearth exposed to form a drying-floor leading to the entrance end of the upper hearth, the other end of the upper hearth being connected with the unexposed end of the 120 lower hearth which is provided with a discharge at or near the end of its exposed portion, the material to be treated traveling over said drying-floor and through the upper hearth in one direction, to then travel in the 125 reverse direction in the lower hearth, said floor being capable of freely taking up the high heat emanating from the outwardly-moving material in the exposed portion of the lower hearth, said floor being also capable of imparting such heat to the material 130 passing into the upper hearth, feed devices for discharging the material to be calcined on the outer end of the said drying-floor,

whereby the material is heated in the open air, to be dried for the purpose described, plowing or agitating devices, means for moving the said devices through the hearths at or 5 near the entrance ends thereof from one to the other, inlets for the products of combustion to the said hearths at or near the entrance ends thereof and an outlet for the products of combustion at the discharge end of the lowermost 10 hearth.

4. A calcining-furnace provided with a plurality of hearths located one above the other, the uppermost hearth being shorter than the hearth beneath it, leaving one end of the roof 15 of the lower hearth exposed to form a drying-floor leading to the entrance end of the upper hearth, the other end of the upper hearth being connected with the unexposed end of the lower hearth which is provided with a discharge at or near the end of its exposed portion, the material to be treated traveling over said drying-floor and through the upper hearth in one direction, to then travel in the reverse direction in the lower hearth, said floor being 20 capable of freely taking up the high heat emanating from the outwardly-moving material in the exposed portion of the lower hearth, said floor being also capable of imparting such heat to the material passing into the upper 25 hearth, feed devices for discharging the material to be calcined on the outer end of the said drying-floor, whereby the material is heated in the open air, to be dried for the purpose described, plowing or agitating devices, means 30 for moving said devices through the hearths from one to the other, a receptacle at the discharge end of the lower hearth, to receive the calcined material and the gases from the lower hearth, inlets for the products of combustion to the said hearths at or near the entrance ends thereof and an outlet for the products of combustion at the discharge end of the lowermost hearth.

5. A calcining-furnace provided with a plurality of hearths located one above the other, 45

the uppermost hearth being shorter than the hearth beneath it, leaving one end of the roof of the lower hearth exposed, the latter being connected at its unexposed end with the discharge end of the upper hearth, feed devices 50 for discharging the material to be calcined upon the exposed portion of the roof or upper wall of the said lower hearth, whereby said material is primarily heated in the open air to be dried, plowing or agitating devices, 55 means for moving the said devices through the hearth from one to the other, a hood for closing the outer ends of the hearths, to make the same practically continuous, a return mechanism for said plowing or agitating devices and contained in said hood, inlets for the products of combustion to the said hearths at or near the entrance ends thereof and an outlet for the products of combustion at the discharge end of the lowermost hearth. 60

6. A calcining-furnace provided with a plurality of hearths located one above the other, the uppermost hearth being shorter than the hearth beneath it, leaving one end of the roof of the lower hearth exposed, the latter being 65 connected at its unexposed end with the discharge end of the upper hearth, feed devices for discharging the material to be calcined upon the exposed portion of the roof or upper wall of the said lower hearth, whereby 70 said material is primarily heated in the open air to be dried, plowing or agitating devices, means for moving the said devices through the hearth from the one to the other, a fire-box at the entrance end of the upper hearth, a fire-box in the lower hearth near the connection between the upper and lower hearths, and a receptacle for the calcined material, such receptacle being below the lower hearth 75 at the end upon which the material is fed.
